UNITED STATES PATENT OFFICE.

HENRY E. SCHRAADER, OF NEW YORK, N. Y.

COLLAPSIBLE LUNCH-BOX.

1,111,619.

Specification of Letters Patent. Patented Sept. 22, 1914.

Application filed May 19, 1914. Serial No. 839,489.

To all whom it may concern:

Be it known that I, HENRY E. SCHRAADER, a citizen of the United States, residing at New York, in the county of New York and 5 State of New York, have invented certain new and useful Improvements in Collapsible Lunch-Boxes; and I do hereby declare the following to be a full, clear, and exact description of the invention, such as will 10 enable others skilled in the art to which it appertains to make and use the same.

This invention relates to collapsible lunch boxes.

One of the principal objects of the invention 15 is to provide a durable paper lunch box which can be quickly expanded for use in carrying a lunch and which can be immediately folded into a flat condition to be carried in the pocket.

20 Another object of the invention is to provide a paper lunch box which can be expanded to contain a lunch and which will be provided with a paper handle extending around the box to form a brace, said handle 25 being formed of a strip of paper which serves as a latch for holding the cover closed and which also serves to hold the box in collapsed or flat condition for carrying in the pocket.

30 These and other objects may be attained by means of the construction illustrated in the accompanying drawings, in which,

Figure 1 is a perspective view of a paper lunch box made in accordance with this invention and showing the cover opened and thrown back, Fig. 2 is a perspective view of the paper lunch box closed, Fig. 3 is a central vertical sectional view of the same, Fig. 4 is a transverse sectional view of the box 40 when folded flat, and Fig. 5 is a plan view of the blank from which the box is formed.

Referring to the drawings, the numeral 1 designates the bottom of the box, 2 are the ends, 3 is the front side, 4 is the back, and 45 5 is the cover. The ends 2 are provided with flanges 6, and when the front and the back 4 are bent upward upon the lines a the flanges 6 are bent at right angles to the ends 2 and secured upon the outer sides of the 50 front and back, as shown more clearly in

Fig. 1. The cover 5 which is formed integral with the body portion of the box is also provided with a down turned flange 7 which overlaps the front edge of the box when closed.

55

A paper strap 8 is secured to the top or cover 5 by means of fasteners 9 to form the handle 10. A ball and socket fastener is utilized for holding the cover closed when the box is expanded and also for holding 60 the box in a collapsed or folded position when empty. The ball member 11 of the fastener is secured to the front of the box and the end of the strap 8 is provided with 65 a socket 12 to receive the ball member and thus hold the box in closed position when expanded.

When the box is empty and in condition to be folded flat, the bottom 1 is folded on the central line b , as shown in Fig. 1, and 70 the ends 2 are folded on a central vertical line c . The bottom 1 is also folded on the converging lines d and when the parts are brought together the strap 8 extends around the box and the end of the strap engages 75 the ball member 11, said strap having a socket member connected thereto at the proper point to hold the box folded flat.

From the foregoing, it will be obvious 80 that a folding lunch box made in accordance with this invention may be formed of paper or leather which will carry a sufficient lunch and when the lunch has been removed, the box can be folded and placed in the pocket to be used the next day. The 85 box is durable in construction, is braced by the handle strap and when folded occupies but little space in the pocket. The lunch box can be cut from a piece of paper without material waste and can be produced at 90 low cost.

Various changes may be made in the details of construction without departing from the spirit and scope of the invention as defined in the claim.

95

What is claimed is:—

A collapsible lunch box made from a single piece of flexible material and comprising a bottom, a front and back, ends having angular flanges secured to the front and 100

back, a folding cover having a down-turned flange and a strap handle comprising a strip of flexible material secured to the top or cover and provided with means to extend beyond the flange of the cover and attach to a fastener, said box being foldable longitudinally at the ends, bottom and top, and said strap adapted to be taken up for

holding the box in either its open or closed condition.

In testimony whereof I affix my signature in the presence of two witnesses.

10 HENRY E. SCHRADER.

Witnesses:

FRANCIS P. COUGHLIN,
JOHN K. WHALEN.
